BABY SUPPORT FOR BATHTUBS

Fred H. Schuette, Des Moines, Iowa

Application May 20, 1938, Serial No. 209,039

7 Claims. (Cl. 4—185)

The object of my invention is to provide a simple, durable and inexpensive means adapted to be detachably secured to the top edge of a bathtub to support a suitable girdle or the like by

means of which a child seated on the bottom of a tub containing a small amount of water may be supported against falling over into the water, the child being supported in such a manner that it may have free use of its arms and feet.

10 More specifically, it is the object of my invention to provide a child support formed of comparatively light and strong material, such as small metal rods, so constructed and arranged that a girdle made of fabric or other similar material

15 may be detachably supported thereby, wherein the girdle may be adjusted as to size and adapted to be supported about the child's waist and wherein the girdle may be easily removed and washed when so desired.

20 In the accompanying drawing

Figure 1 is a transverse sectional view of one side of a bathtub showing my improved device in side elevation and the manner in which the same is supported in the tub.

25 Figure 2 is an end elevation of the device as it is detached from the tub.

Figure 3 is a top view of the device.

My improved baby support comprises a supporting frame 10 formed preferably of a single 30 piece of rod on which a rubber tube 11 is supported and moved to the central portion of the rod, after which the rod is bent to form a loop 12, said loop portion then being bent at right angles to provide upwardly extending leg portions

35 13, one of which is formed longer than the other and supported adjacent thereto, as clearly shown in Figure 2. The rods are then again bent at right angles to be supported in horizontal planes, and formed with curved portions 14. The lower

40 one of the rods is then bent upwardly at 15, the said portion 16 is then again bent at right angles to assume a horizontal position and adjacent to the upper member 14, the last said horizontal portions being designated by the numeral 16, the

45 rods being welded or otherwise fixed together. The ends of the portion 16 are then bent upwardly and diverging from each other, as clearly shown in Figure 2, their upper ends terminating in hook portions 17 and downwardly extending

50 portions 18, the lower ends of the portions 18 being bent inwardly toward each other and adapted to be placed in a sleeve 19, said sleeve providing means for fixing the ends of the members 18 and also as a means for supporting a

55 set screw 20 having on its inner end a foot 21

which may be faced with an elastic member 22, such as rubber, the outer end of the screw 20 being formed in a loop 23 to provide a handle by means of which the screw 20 may be operated.

The upwardly divergent portions and the hooks 17 are provided with a rubber covering 24 such as a rubber tube. Thus, means is provided whereby the hook portion 17 may be placed over the flange 25 of a bathtub 26, with the loop mem-

ber 12 resting on the bottom 27 to serve as a support for the inner end of the frame 10, while the hooks 17 provide a support for the outer end of the frame, the hooks 17 being spaced apart to provide means for supporting the free end of the frame against swinging movement. The set 18

screw 20 and the foot 21 provide a means for fixing the frame to the tub to prevent the same being moved longitudinally of the tub. The loop portions 14 provide means for supporting a girdle 28, which is preferably formed of a washable 20

fabric, having glove fasteners 29 for detachably and adjustably securing the ends of the girdles together whereby the girdle may be placed around the waist of a child sitting on the bottom of the tub, and having its ends secured together to support the child in an upright position, one side of the girdle 28 being provided with straps 30, having their ends provided with glove

35 fasteners or other suitable fastening means 31 for fastening the ends of the straps together, said straps being adapted to be placed around the curved portions 14, as indicated in Figures 2 and 3, and when so placed, provide means for holding the girdle in place. By providing two curved

30 portions 14, one above the other, means is provided whereby the girdle may be more positively supported so as to assume a horizontal position. The two curved portions also provide means for

35 supporting both the lower and upper edges of the girdle and apply the supporting forces over a greater amount of area on the child's body.

40 Thus, it will be seen I have provided a support of simple and cheap construction which may be easily and quickly placed in operative position and so constructed that the girdle will be firmly supported and held against movement, at the same time providing means whereby the child may be supported against falling over, and at

45 the same time permitting free movement of the 50 child's arms and feet so that it may amuse itself by splashing the water in which it is sitting.

I claim as my invention:

55 1. A baby support for bathtubs, comprising a supporting frame having one end adapted to rest

- on the bottom of a bathtub, means for detachably securing the other end of said frame to one edge of the tub, an adjustable girdle, and means for detachably securing the girdle to said frame.
5. 2. A baby support, comprising a body portion supported substantially in a horizontal position, having an upwardly extending hook portion at one end adapted to rest on the upper edge of a bathtub, a clamping device carried by said hook, 10 said body having a downwardly extending portion at the other end to rest on the bottom of the interior of the tub, an adjustable and washable girdle, and means detachably securing the girdle to the horizontal portion of the body.
15. 3. A baby support, comprising a frame formed of a single piece of metal rod folded at its central portion to provide over-lapping portions, the folded end being formed into a loop to provide a foot portion, the ends of said loops terminating in 20 upwardly extending leg portions, thence into separated horizontal curved portions one above the other, said curved portions terminating in adjacent horizontal portions, said portions being adjacent and fixed together, the outer end of 25 said horizontal portion terminating in upwardly and diverging portions, which in turn provide hooks having their lower ends projected downwardly and terminating in inwardly extending portions, a sleeve connecting the said inwardly 30 extending portions, a horizontal set screw mounted in said sleeve, a girdle, and means for detachably securing said girdle to the curved portions of said frame.
4. A baby support, comprising a body having a
- curved portion supported substantially in a horizontal plane, means for supporting the said curved portion of said body above the bottom of a bathtub, a girdle, means for adjustably connecting its ends together, a series of vertical straps carried by said girdle, means for detachably securing the ends of said straps together to form loops, said loops being formed around the curved portion of said body whereby the girdle may be placed around the waist of a baby sitting on the bottom of the tub, to support it against falling over. 5
5. A baby support for bathtubs, comprising a supporting frame having one end adapted to rest on the bottom of a bathtub and the other end on 15 the upper edge of one side of the tub, a girdle, and means for detachably securing the girdle to the supporting frame.
6. A baby support, comprising a frame having a curved portion in a substantially horizontal 20 plane, means supporting said frame above the bottom of a bathtub, a washable girdle, and means for detachably securing said girdle in the curved portion of said frame whereby the girdle may be easily removed for washing. 25
7. A baby support, comprising a frame having a curved portion in substantially a horizontal plane, means supporting said frame above the bottom of a bathtub, a washable and adjustable girdle, and means for detachably securing said 30 girdle in the curved portion of said frame whereby the girdle may be easily removed for washing.
